The ornamental design for a lavatory, as shown and described.

DESCRIPTION

FIG. 1 is a perspective view taken from the top, front and right side of a lavatory showing our new design;

FIG. 2 is a top plan view thereof;

FIG. 3 is a cross-sectional view thereof taken on line 3—3 of FIG. 2;

FIG. 4 is a cross-sectional view thereof taken on line 4—4 of FIG. 2;

FIG. 5 is a cross-sectional view thereof taken on line 5—5 of FIG. 2;

FIG. 6 is a cross-sectional view thereof taken on line 6—6 of FIG. 2;

FIG. 7 is a cross-sectional view thereof taken on line 7—7 of FIG. 2; and,

FIG. 8 is a cross-sectional view thereof taken on line 8—8 of FIG. 2.

The fragmentary broken line representation of fitting mounting holes in FIGS. 1 and 2 is for the purpose of illustration only and forms no part of the claim design.
